US00D672559S

(12) **United States Design Patent**
Nash

(10) **Patent No.:** US D672,559 S
(45) **Date of Patent:** ** Dec. 18, 2012

(54) **OPEN-ENDED CONTAINER**

(75) Inventor: **Jaime W. Nash**, Lake Tapps, WA (US)

(73) Assignee: **Wilmar Corporation**, Renton, WA (US)

(**) Term: **14 Years**

(21) Appl. No.: **29/417,221**

(22) Filed: **Mar. 30, 2012**

Related U.S. Application Data

(62) Division of application No. 29/400,158, filed on Aug. 24, 2011.

(51) **LOC (9) Cl.** 03-01

(52) **U.S. Cl.** D3/304

(58) **Field of Classification Search** D3/304, D3/310, 315; D6/449, 470-473, 509-510; D7/601-602, 605, 612-614, 701; 312/114-117; 206/503-504; D9/424-426; 220/23.2-23.6, 220/23.83

(57) **CLAIM**

The ornamental design for an open-ended container, as shown and described.

DESCRIPTION

This application is also related to U.S. patent application Ser. No. 29/400,169, filed on Aug. 24, 2011 and entitled “Open Ended Container,” to U.S. patent application Ser. No. 29/400, 177, filed on Aug. 24, 2011 and entitled “Open-Ended Container System,” and to U.S. patent application Ser. No. 29/417,229, filed on even date herewith and entitled “Open-Ended Container.”

FIG. 1 is a front perspective view of an open-ended container embodying my new design;

FIG. 2 is a top view of the open-ended container of FIG. 1;
FIG. 3 is a front view of the open-ended container of FIG. 1;
FIG. 4 is a side view of the open-ended container of FIG. 1;
FIG. 5 is a rear view of the open-ended container of FIG. 1;
and,

FIG. 6 is a bottom view of the open-ended container of FIG. 1.

The broken lines shown herein are included for the purpose of illustrating the environment of the design and form no part of the claimed design.
